UNITED STATES PATENT OFFICE.

OTTO FOX, OF LAKEWOOD, OHIO, ASSIGNOR TO THE BRYANT HEATER & MANUFACTURING CO., OF CLEVELAND, OHIO, A CORPORATION OF OHIO.

FEED-WATER CONTROL FOR BOILERS.

1,246,079.

Specification of Letters Patent. Patented Nov. 13, 1917.

Application filed September 17, 1915. Serial No. 51,137.

To all whom it may concern:

Be it known that I, OTTO FOX, a citizen of the United States, residing at 1602 Woodward avenue, Lakewood, in the county of Cuyahoga and State of Ohio, have invented a certain new and useful Improvement in Feed-Water Controls for Boilers, of which the following is a full, clear, and exact description.

10 This invention relates to feed water control for boilers and has for one of its objects to provide a construction such that the float controlled valve or valves may be easily adjusted from the exterior of the float 15 chamber.

A further object is to provide a construction wherein the valve or valves and the mechanism for operating the same may be removed as a unit from the float chamber 20 by removing a detachable part of the chamber and without necessity for disconnecting any of the piping.

The invention may be briefly summarized as consisting in certain novel details of construction and combinations and arrangements of parts which will be described in the specification and set forth in the appended claims.

In the accompanying sheets of drawings, 30 Figure 1 is an elevation of a boiler equipped with the invention; Fig. 2 is an end elevation of the feed water controlling mechanism detached from the boiler; Fig. 3 is a vertical sectional view of the same; Fig. 4 35 is a horizontal sectional view substantially along the line 4—4 of Fig. 3 looking in the direction indicated by the arrow; Fig. 5 is a detached side view of the overflow valve and some of the parts immediately associated 40 with the valve; and Fig. 6 is a top view of the same.

In the drawings, 10 represents a boiler which may be of any suitable construction and 11 represents the casing or chamber 45 inclosing the parts which control the feed of water to the boiler, which chamber or casing may for the sake of brevity be termed the float chamber. The upper part of this chamber is connected by a pipe 12 to the upper part of the boiler or to a pipe leading thereto, and the lower part of the cham-

ber 11 is connected by a pipe 13 to the lower part of the boiler or to a pipe leading thereto, so that the water level in the chamber 11 will always be the same as the water 55 level in the boiler 10. The chamber 11 may be provided with a gage glass 14 and with try-cocks 15, but these parts are not essential to the invention.

The chamber 11 is substantially L-shaped, 60 as viewed from the side, the said chamber having an upright portion and a lower horizontally extending portion the end of which is closed by a plate or cap 16 secured by a series of bolts 17 to the flanged open end of 65 the lower part of the casing. This plate 16 carries all the operating parts which control the feed of water to the boiler and also the overflow from the boiler, as will be subsequently explained. In this instance I 70 have provided in the chamber two floats and on the plate 16 I have provided two valves, one of which controls the admission of water to the boiler and the other controls the overflow or flow of water from the boiler, 75 the valves being so operated that when the water level falls below a predetermined level the inlet or feed valve will be operated to admit water to the boiler, and when the water level in the boiler exceeds a predetermined limit (due to the water running back through the pipes to the boiler, especially that resulting from condensed steam) the overflow valve will be opened so as to permit 80 said excess to flow from the boiler. The inlet valve 18 and the overflow or outlet valve 19 consist of needle valves which are arranged side by side, as shown most clearly in Fig. 4. These valves are mounted for movement in separate valve supporting 85 members 20 and 21 having threaded portions 22 which are screwed into portions of the detachable end plate 16. The member 20 supporting the inlet valve is screwed into the inner wall of an inlet chamber 23 formed 90 in a cored boss on the outer side of the plate 16 while the valve supporting member 21 for the overflow valve 19 is screwed into the inner wall of an outlet chamber 24 formed 95 in a similar boss on the outside of the 100 plate 16.

These two needle valves 18 and 19 have

2
adjustable valve seats 25 and 26 which are arranged horizontally in line with the valves and which have their outer ends on the exterior of the chamber or of the plate 5 16 so that they can be readily adjusted to vary the timing of the valves, *i. e.*, to adapt the inlet and overflow valves to operate at different water levels. These two valve seats have threaded inner portions which are 10 screwed into the ends of the corresponding valve supporting members 20 and 21 and each valve seat passes through a pair of stuffing box glands including glands 27 for preventing leakage of water to the exterior 15 of the float chamber.

Both valves 18 and 19 are mounted for endwise movement in flanges 28 projecting from the body portions of the valve-supporting members 20 and 21. It may be observed at this point that the position of one 20 of the valve-supporting members is reversed with respect to the position of the other, that is to say, the flanges 28 in one instance extend upwardly and in the other instance 25 extend downwardly.

The inlet valve 18 is operated by a float 29 which is connected by a float rod 30 extending over the valve and valve-supporting member to the upper part of a swinging yoke or stirrup 31 to which the rod is rigidly attached, which yoke or stirrup is pivoted at 32 to the corresponding valve-supporting member 20. This member 31 is connected by a pair of straps or links 33 to 30 an enlargement in the nature of a boss 34 at the outer end of the valve, *i. e.*, at the end 35 of the valve remote from the valve seat. It will be seen that as the float falls it has a tendency to move the inlet valve away from 40 its seat, and as the float rises it has a tendency to move the valve toward the seat.

The overflow valve 19 is operated by a float 35 to which is attached a float rod 36 which extends beneath the corresponding 45 valve-supporting member 21 (see Fig. 5) and is attached to the lower part of a yoke or stirrup 37 which is similar in all respects to the yoke or stirrup 31 but is inverted with respect thereto. This member 37 which 50 is pivoted to the valve-supporting member 21 as in the first instance, is connected by straps or links 38 to a boss 34 at the outer end of the overflow valve 19. It will be seen that with this arrangement of parts as the 55 float 35 rises it has a tendency to open the overflow valve, and as it falls it has a tendency to close the valve.

Both the valve seats have ports or passageways 39 extending from the inner end 60 outwardly and thence laterally, one passageway extending to the inlet chamber 23 and the other to the outlet or overflow chamber 24.

On one side of the float chamber wall near

the flanged end to which the detachable plate 65 16 is secured is a hollow boss or chamber 40 having a tapped opening 41 to which a feed pipe 42 is connected (see Fig. 1). This boss or enlargement 40 is provided also with a cored opening 42 communicating with the 70 tapped opening 41 and extending to a cored opening 43 which is in the detachable plate 16 and extends to the inlet chamber 23. Directly opposite the boss 40 to which the 75 inlet pipe is attached or on the opposite side of the float chamber, there is a similar boss 44 having a tapped opening 45 for an overflow pipe and a cored opening 46 extending to and registering with a cored opening 47 which is in the detachable plate 80 16 and extends to the overflow or outlet chamber 24.

When the end plate 16 is fastened in position on the float chamber, water is free to pass from the inlet or supply pipe (which is 85 connected to the float chamber independently of the end of the plate) through the registering cored openings 42 and 43 to the inlet chamber 23, and when the water falls to a predetermined level in the boiler the inlet valve 18 is opened permitting the water to pass from the chamber 23 through the port or passageway in the valve seat for inlet needle valve 18 to the float chamber, and hence to the boiler. When a certain 90 amount of water has run into the boiler the rising of the float controlling the inlet valve will close the latter. In a similar manner the outlet or overflow chamber 24 is in communication through the registering cored 95 openings with the overflow pipe which, as before stated, will be connected in the tapped opening 45. If the water rises beyond a certain predetermined level the outlet valve is opened and the water will drain from the float chamber and from the boiler until it reaches a predetermined lower level, in which event the overflow valve is closed.

It will be observed, further, that by reason 100 of the fact that the valve seats extend endwise through the plate 16 to the exterior of the chamber, the positions of the valve seats can be adjusted from time to time without opening the chamber or inserting a tool into the same, whenever it is necessary to adjust the timing of the valves or the high and low water levels at which the valves are operated.

A still further important advantage of 105 this construction lies in the fact that by removing the plate 16 both valves and all the valve controlling and supporting parts are removed as a unit for repairs, cleaning or replacement, and, this can be done without disconnecting any piping whatever since the feed and overflow pipes are connected to the body portion of the float chamber and not to the end plate.

I have shown only the preferred construction wherein there are two valves, one for controlling the feed water and the other for controlling the overflow, and while I prefer to use both valves in the manner here shown, I wish it to be understood that my invention can be advantageously employed with a single valve, viz: an inlet valve. In other words, as far as certain details of my invention are concerned the overflow valve may be omitted. The inlet or feed valve will be employed alone whenever the conditions of the boiler or steam lines connected to the boiler are such that means for carrying away the overflow or excess water is not required or desired.

I do not desire to be confined to the exact details shown, but aim in my claims to cover all modifications which do not involve a departure from the spirit and scope of my invention.

Having thus described my invention, what I claim is:—

1. In a feed water control for boilers, a float chamber including a removable plate, a float in the chamber, a valve supporting member carried by said plate, a valve supported for endwise movement by said member, a valve seat carried by said plate and extending through the same to the exterior thereof whereby the seat may be adjusted relative to the valve, means operatively connecting the float to the valve so that the valve will be opened when the water reaches a predetermined low level in the chamber and will be closed when the water reaches a predetermined high level therein, and means separate from the outer end of the valve seat for supplying water to the chamber through the valve.

2. In a feed water control for boilers, a float chamber, a float therein, a valve supporting member carried by the chamber, a valve supported by said member, a valve seat for said valve extending to the exterior of said chamber whereby the seat may be adjusted relative to the valve, means operatively connecting the float to the valve so that the valve will be opened when the water reaches a predetermined low level and will be closed when the water reaches a predetermined high level in the chamber, said chamber comprising a body portion and a removable plate, the latter supporting said valve supporting member, the valve, the valve seat and the float, said valve seat having an opening for the passage of water, and passageways for supplying water to said opening and comprising a passageway in the plate and a passageway in the body portion of the chamber registering with said passageway in the plate.

3. In a feed water control for boilers, a float chamber, a valve supporting member

supported by the chamber, a needle valve 65 supported for endwise movement by said member, a valve seat for said valve extending to the exterior of the chamber whereby it may be adjusted relative to the valve, means connecting the float to the needle 70 valve so that the valve will be opened when the water in the chamber reaches a predetermined low level and will be closed when the water reaches a predetermined high level, the chamber comprising a body portion and 75 a removable plate carrying the valve supporting member, the valve, the seat and the float, and passageways extending through portions of said plate and of said body portion of the chamber for supplying water 80 through the valve to the chamber.

4. In a feed water control for boilers, a float chamber, comprising a body portion and a detachable plate secured thereto, an inlet valve and valve seat, an outlet valve 85 and valve seat, said valves being arranged side by side, a pair of floats for controlling said valves, said valves, valve seats and floats being carried by said detachable plate.

5. In a feed water control for boilers, a float chamber, comprising a body portion and a detachable plate secured thereto, an inlet valve and valve seat, an outlet valve and valve seat, said valves being arranged side by side, a pair of floats for controlling 95 said valves, said valves, valve seats and floats being carried by said detachable plate, said body portion of the casing having means for attachment thereto of a feed water pipe and an overflow pipe. 100

6. In a feed water control for boilers, a float chamber comprising a body portion and removable plate, an inlet valve, a float for operating the same, a valve seat, an inlet chamber, said valve, valve seat, float and inlet chamber being carried by the plate and removable as a unit therewith, the valve seat having a passageway for permitting passage of water from said inlet chamber to the float chamber, said body portion having means for forming a connection with a feed pipe and passageway extending from said means to said inlet chamber of the plate. 105

7. In a feed water control for boilers, a float chamber comprising a body portion and a removable plate attached thereto, two valves for controlling respectively the admission to and exhaust of water from the chamber, a pair of floats in the chamber each operatively connected to one of the valves, said removable plate carrying the valves and the floats and being removable therewith as a unit from the body portion of the chamber. 110

8. In a feed water control for boilers, a float chamber comprising a body portion and a detachable plate secured thereto, the

body portion having pipe connections for a feed water pipe and an overflow pipe, and the plate having inlet and overflow chambers communicating respectively with said feed water and overflow pipe connections, two valves and two floats in the chamber, the floats being operatively connected to the valves so as to control the passage of water

between said float chamber and the inlet and overflow chambers of the plate, said valves and floats being carried by said plate and being removable therewith as a unit from the body portion of the float chamber. 10

In testimony whereof, I hereunto affix my signature.

OTTO FOX.
